UNITED STATES PATENT OFFICE.

JOSEPH M. MERROW, OF HARTFORD, CONNECTICUT.

DESIGN FOR A SEWING-MACHINE FRAME.

53,929.

Specification for Design.

Patented Oct. 7, 1919.

Application filed February 21, 1917. Serial No. 150,272. Term of patent 14 years.

To all whom it may concern:

Be it known that I, JOSEPH M. MERROW, a citizen of the United States, residing at Hartford, in the county of Hartford and State of Connecticut, have invented a new, original, and ornamental Design for Sewing-Machine Frames, of which the following is a specification, reference being had to the accompanying drawings, forming part thereof.

Figure 1 is a front side view; and Fig. 2 is an end view of a sewing machine frame showing my new design.

I claim:

The ornamental design for a sewing machine frame, as shown.

JOSEPH M. MERROW.

Witness:

THOMAS DURANT.
